UNITED STATES PATENT OFFICE.

ELMER S. SEAVEY, OF JOHNSTOWN, PENNSYLVANIA.

MULTIPLE-DRILLING MACHINE.

Application filed December 1, 1919. Serial No. 341,653.

To all whom it may concern:

Be it known that I, ELMER S. SEAVEY, a citizen of the United States, and residing in the city of Johnstown, in the county of Cambria and State of Pennsylvania, have invented certain new and useful Improvements in Multiple-Drilling Machines; and I do hereby declare the following to be a full, clear, and exact description of the invention, 10 such as will enable others skilled in the art to which it appertains to make and use the same.

My invention relates to a machine for drilling rolled metal shapes, such as rail-way rails, angles, I-beams, channels, flats, round and the like, and is more especially adapted for use in the perforation of railway rails, just after they have been rolled and hot-sawed and while still in a red hot or 20 heated condition, although I wish it understood that my improved drilling machine is equally applicable for drilling cold metal shapes either with one hole, or a plurality of holes at the same time as desired.

Heretofore it has been customary after a railway rail bar leaves the final or finishing roll pass for it to be received on a roller feed table at the side of which it is held stationary for a few seconds and cut into the desired lengths by means of rotary hot saws. After having cut the railway rail bar into the desired lengths the rails are conveyed to a hot-bed to cool, after cooling, the ends of the rails are chipped or milled to remove 35 the burred edges of the ends of the rails caused by hot-sawing, and the rails are then conveyed to a drilling machine where holes are drilled near the ends of each rail, through which the rail splicing joints bolts 40 pass when the ends of the rails are spliced together to form a railway track.

The above manner of finishing the rails requires considerable handling and loss of time and labor, and it is the object of my invention to reduce the time and labor required to finish a railway rail section and thereby reduce the cost of production.

An object of my invention is to provide a machine with means whereby the drills 50 are advanced and retracted quickly and as

the same time the drills are rotated at high speed, to prevent tearing of the metal as the drills pass through the bar being drilled.

Another object of my invention is the manner I have of providing a main central 55 stationary driving gear for rotating a plurality of drill spindle driving gears arranged around the periphery of the main driving gear and mounted in movable journal bearings whereby they may be 60 thrown into or out of mesh with the main driving gear, by means of which I can drive one or a plurality of drill spindles as desired.

A further object of my invention relates to 65 arranging two reciprocating carriages side by side having a plurality of adjustable drill spindle bearings mounted thereon, and having a central gage or stop which may be either laterally adjustable or stationary 70 upon the work receiving table. By this arrangement, when the drill spindle bearings are adjusted on the two carriages to give the proper spacing for the holes to be drilled, the front end of one rail can be drilled by 75 the drills carried by the bearings on one carriage and the rear end of another rail may be drilled by the drills carried by the bearings on the other carriage. In this way two ends of rails may be drilled by one so operator at the same time or separately as desired.

Another object of my invention relates to controlling the speed of the forward movement of the drills during the drilling operation, whereby the drills may be advanced very quickly, as is required when drilling hot rolled bars, to prevent the drills from losing their temper, or comparatively slow when cold bars are drilled and adjustable 85 means for retracting the carriages at the end of the working stroke to the position they will assume at the commencement of the working stroke.

A further object of my invention relates 95 to the means I have for adjusting the drills upon laterally adjustable carriages with means for adjusting the stroke of the carriages longitudinally.

Another object of my invention relates to 100

advancing by fluid pressure the carriages upon which the spindle bearings are mounted.

Another object of my invention resides in the construction of the clamping and releasing members and the manner I have of adjustably attaching the face of the clamping members thereto.

Still another object of my invention relates to the adjustable spring holding members for the movable clamping jaws.

Other objects of my invention will appear hereinafter.

Having thus given a general description of my invention I will now, in order to make the same more clear, refer to the accompanying nine sheets of drawings in which like characters of reference indicate like parts:

20 Figure 1 is a top plan view of one form of my improved machine, the rail being fed into the machine in an upright or standing position; with its web vertical, showing two reciprocating carriages having sets of 25 drill spindles and bearings adjustably mounted thereon, with a single means for driving the two sets of drill spindles mounted in a stationary pinion housing and having universal shaft connections between the 30 driving mechanism and the drill spindles.

Figure 2 is a side elevation of the machine shown in Figure 1.

Figure 3 is a vertical transverse sectional elevation through the pinion housing taken 35 on the line III—III of Figure 4 drawn on a larger scale.

Figure 4 is a rear elevation of the pinion housing.

Figure 5 is a vertical transverse sectional 40 elevation of a portion of the machine showing more particularly the reciprocating carriages and their adjacent parts, taken on line V—V of Figure 6.

Figure 6 is a vertical longitudinal sectional elevation taken on the line VI—VI 45 of Figure 5.

Figure 7 is a vertical longitudinal sectional elevation of one of the bearings for the adjustable clamping members.

50 Figure 8 is a vertical longitudinal sectional elevation taken on the same line as Figure 6, but showing a modification of the carriage construction.

Figure 9 is a side elevation of one of the 55 journal bearings, and a portion of the carriage to which it is attached, the lower part of the bearing being shown in section to more clearly show its construction.

Figure 10 is a longitudinal sectional elevation through the drill spindle bearing 60 taken on the line X—X of Figure 9.

Figures 11 and 12 show two sections taken on the same line as Figure 10 but illustrating modified forms of bearings which I may 65 use.

Figure 13 is a transverse sectional elevation through one of the universal coupling heads taken on the line XIII—XIII of Figure 11.

Figure 14 is a vertical transverse sectional elevation taken on the line XIV—XIV of Figure 2, showing in elevation the work receiving table with fixed clamping block mounted thereon.

Figure 15 is a vertical sectional elevation 75 through the work receiving table taken on the line XV—XV of Figure 14.

Figure 16 is a vertical sectional elevation through the work receiving table, the section being taken on a line with one of the 80 holes bored by my improved machine.

Figure 17 is a transverse section through one of the movable clamping jaws.

Figure 18 is a vertical longitudinal sectional elevation of a portion of the work receiving table taken on the line XVIII—XVIII of Figure 15.

Figure 19 is a detail view showing a motor and bevel gear connection which I may use with a modified form of machine shown in 90 Figure 20.

Figure 20 is a front elevation illustrating a modified form of my improved machine in which the rail is fed into the machine on its side, with the web of the rail horizontal, 95 the carriages being reciprocated vertically by fluid pressure, the drill spindles for each carriage being driven by separate motors and pinion housings and having a central gage or stop on the work receiving table 100 which is movable transversely of the work receiving table but not laterally thereon.

Figure 21 illustrates in detail the bevel gear connection used with the motor drive 105 shown in Figure 19.

Figure 22 is a vertical transverse sectional elevation through a modified form of stationary clamping head which I may use with my modified form of machine shown in 110 Figure 20.

Figure 23 is a side elevation of one of the pinion gear housings used with the machine illustrated in Figure 20.

Figure 24 illustrates in top plan the fluid pressure controlling mechanism for reciprocating the carriages.

Figure 25 is a vertical sectional elevation taken on the line XXV—XXV of Figure 23.

Figure 26 is a vertical transverse sectional 120 elevation taken centrally through the work receiving table of the machine shown in Figure 20.

Figure 27 illustrates in detail the controlling lever.

Figure 28 shows in detail the link connections between one of the controlling valves and one of the operating shafts.

Figure 29 is a vertical transverse sectional elevation taken centrally through a 130

table similar to that shown in Figure 26, but illustrating a modified form of gage controlling means therefor.

Figure 30 illustrates a modified arrangement for the pinion driving mechanism, and

Figure 31 is a vertical sectional elevation of the controlling valves.

Referring now to the characters of reference on the drawings and especially to Figures 1 to 18 inclusive, the numeral 1 indicates the side-base frame of the machine, 2 the rear end thereof and 3 the front of the frame-work of the machine, upon which is mounted the work receiving table. The 15 end walls 2 and 3 of the machine are attached together by means of bolts at the bottom side edges of the side-base frames 1, and near their top side edges by the top side frames 4, each having outwardly 20 flanged edges 5 and slide-ways 6. The top side frames 4 are connected together intermediately thereof by two cross-ties 7, for supporting the ends of a central slide-way member 8, having flanged edges 9 and slide-ways 10.

Reciprocating carriages 11 and 12, of similar construction and operation are mounted on the slide-ways 6 and 10, each having an adjustable face plate 13, seated in a dove-tailed recess 14, on the face of each of the carriages. These face plates 13 are adjustable transversely of the machine by screw-threaded shafts 15, engaging the screw-threaded nuts 16, projecting from the face plates and the ends of said shafts are journaled in the carriages 11 and 12 respectively and operated by means of hand wheels 17. Extending from the central portion of the top of the face plate 13, is a dove-tailed projection 18, extending into dove-tailed grooves in the underside of the drill-spindle journal bearings 19. The drill-spindle journal bearings 19 are adjustable laterally of the machine by means of a hand wheel 20, having a shaft 21 journaled in the lower portion of the drill-spindle journal bearing 19, upon which is mounted in an opening therethrough a pinion 22, meshing with a rack 23 on top of the dove-tailed projection 18. After adjustment the drill-spindle journal bearings 19 are further held in the desired position by means of set bolts 24, as clearly shown in Figure 9 of the drawings.

25 indicates the drill-spindles, each having a drill socket attached to its forward end, which may be of any approved and well known construction as shown. A collar 26 is formed integrally on the drill-spindle shaft 25 and as illustrated in Figure 10, abuts against the end of the inner cone of a "Timken" roller bearing 27, and is adjustably held in position by nuts 28 and 29, screwed upon the drill-spindle shaft. The 65 rear end of the drill-spindle shaft is also

supported by a "Timken" roller bearing 30 and held in position by a nut 31 and the dust cap 32, which also acts as a locknut, and a similar dust cap 33 is attached to the forward side of the bearing, through which the drill-spindle shaft passes.

In Figure 11 I have shown a drill-spindle journal bearing 34 of a slightly modified form, in which I use ball bearings 35, instead of roller bearings, and in Figure 12, I 75 have illustrated a drill-spindle journal bearing 36, in which I use another form of ball-bearings 37, otherwise it will be noted all of the bearings are similar. It will also be noted that although I have shown the nuts 80 28 and 29 for securing one side of the roller or ball bearings in position I may in some cases dispense with them altogether and rely upon the collar 26, and the wall of the drill-spindle journal bearing and use the nuts 31 85 and dust caps 32, for adjustment.

To the rear end of the drill spindle-shaft 25, is keyed a universal coupling head 38, between the bifurcated ends of which, are two blocks 39, of similar construction having grooves for the reception of the head of stud 40 and the stud-pin 41, and a hole therethrough as at 42, for the bolt 43. The stud 40 and the stud-pin 41 extend into holes in the bifurcated ends of the universal coupling head and held in position by the bolt 43, which passes through the bifurcated end of the coupling-shaft 44 and the two blocks 39, and has one end screwed into one of the bifurcated ends of the coupling-shaft 100 44, as will be clearly understood by referring to Figures 11, 12 and 13 of the drawings.

The coupling-shaft 44 has an inner shaft 45, and the two telescope together and have a spline 46, which allows them to slide one within the other and to rotate together. A similar universal joint is made between the rear end of shaft 45 and the front end of the drill-spindle driving shaft 47 by means of the universal coupling heads 48 and 49 110 respectively.

The pinion housing is mounted upon a bed plate 50 and bolted or otherwise secured thereto and comprises a casting having a front wall 51, with flanged side walls 52 and base flanges 53, formed integrally therewith, and a rear wall 54, made of a flat plate which is attached to the front wall casting by means of bolts 55.

Slide-ways 56 are formed in the front 120 casting of the pinion housing for the reception of the journal bearings 57, for the drill-spindle driving shaft 47. These bearing members 57, are bifurcated as at 58, centrally, to allow for a pinion 59 to be mounted upon the driving shaft 47. The bearing members 57 have outwardly extending bosses on each side of the bifurcated central portion 58, as at 60, which extend through slotted openings 61 in the front and rear 130

walls of the pinion housing, in which are mounted "Timken" roller bearing 62, or the like, and a nut 63 and dust cap 64, are screwed within the ends of the bosses and retain the bearings in place therein. These "Timken" roller bearings form the journal bearings for the drill-spindle driving shaft 47, as more clearly illustrated in Figures 3 and 4 of the drawings.

16 Mounted centrally in the front and rear walls of the pinion housing, is a main drive shaft 65, journaled in stationary bearings 66, having "Timken" roller bearings 67, and each having retaining nut 68 and dust cap 69 for holding the roller bearings in position.

17 A gear 70 is keyed to the main drive shaft 65, between the bearings 66, for meshing with pinions 59 mounted on drill-spindle driving shafts 47. To the outer end of each of the bearing members 57, is formed a T-slot as at 71 for the reception of the T-shaped head 72, of the wheel screw bolt 73, controlled by a hand wheel 74. By turning 20 the hand wheel 74 to the right or left the bearing member 57 may be raised or lowered as desired, to throw the pinion 59 out, or into engagement with the main drive gear 70. As will be noted by referring to Figure 3 25 of the drawings I have allowed considerable space between the outer edge of the pinions 59 and the central wall of the bearing members 57, thereby allowing a considerable change in the sizes of gearing used when a 30 different driving speed is desired.

18 A bed-plate 75 is mounted on the rear end of the machine, upon which is adjustably secured a motor 6, having a shaft 77 coupled as at 78, directly to the main drive shaft 65, thereby furnishing a direct drive for the main drive shaft.

19 The front end frame 3 of the machine carries a vertical slideway 79, upon which is mounted the work receiving table 80, having the usual adjusting screw support 81 and hand wheel 82 for raising and lowering the work receiving table.

20 A clamping block 83 is mounted upon the work receiving table and is rigidly held in position thereon by having lugs 84, which project from the base of the clamping block 83 into slots 85 in the table and bolts 86 are screwed into the lug projections, thereby rigidly securing the clamping block 83 upon the table. The slots 85 being considerably longer than the projections 84, allows the clamping block to be adjusted transversely of the table by means of the bolts 86, as clearly illustrated in Figures 14, 15 and 18 of the drawings.

21 A T-shaped guide-way 87 is formed in the top of the clamping block 83, in which two guide blocks 88, 89 are mounted each having a pair of upwardly extending ears 90, between each of which the end of an

L-shaped stop or gage 91, is pivoted by means of a bolt 92. To the ends of each bolt 92 is keyed a hand lever 93 for operating the gage or stop 91, and having a counter-weight 94, attached thereto for holding the gage more securely in its raised or lowered position. Each stop or gage is made to reciprocate longitudinally of the table by means of feed screws 95, operated by hand wheels 96, for setting the stops 75 or gages 91 in the desired position.

22 On one side of the clamping block 83 is an integrally formed projection 97, being grooved on its under side as at 98, and having on its side face vertical notches 99, and a longitudinal dove-tailed recess 100 for receiving the dove-tailed projection 101 of the contact face plate 102. The inner lower surface of the vertical notches 99 are inclined to contact with the heads of the wedge-bolts 85 103, the threaded ends of which extend above the ends of the notches and have nuts 104 thereon. By this manner of securing the contact face plate 102 to the projection 97, the contact face plate may be adjusted longitudinally and securely locked in any desired position by means of the bolts 103. A slot 105 is formed in the face of the projection 97 and extends longitudinally nearly to the ends thereof, connecting the groove 98 with the dove-tailed recess 100 and registers with the holes 106 in the contact face plate 102, through which the drills project at the end of the working stroke.

23 Mounted upon the dove-tailed projections 100 18, at each side of the carriages is a bearing or support 107, each having a bolt 108 extending through a hole 109 in each of the upper portions thereof. These bolt heads abutting against the side of their respective bearing, the forward end of each bolt being screwed into the movable clamping block 110, and a helical spring 111 surrounds the body of each bolt 108. One end of the helical spring engaging the side of the movable clamping block, while the other end is seated in a socket 112, in the bearing or support 107, thereby holding the movable clamping block 110 always in an extended position. The lower portion of each of the 105 bearings or supports are of similar construction to the lower portions of the drill-spindle journal bearings 19, having a dove-tailed groove in their undersides for receiving the dove-tailed projection 18, and are adjustable laterally by means of hand wheels 113, having a shaft 114, upon which is mounted a pinion 115, meshing with the rack 23, and a set bolt 116 for holding the bearing against displacement. Each of the 110 movable clamping blocks 110 has its contact face constructed similar to the faces of the stationary clamping members, having longitudinal dove-tailed grooves 117, for receiving the dove-tailed projections 118 of 115

120 125 130

the contact face plates 119 and, vertical grooves 120, with inclined inner lower faces for the reception of the wedge bolts 121, and are held in position by means of nuts 122.

5 The movable clamping blocks are also slotted as at 123 and the contact face plates 119, have holes 124, for the passage of the drills.

10 Each carriage is advanced by means of a fluid pressure cylinder 125, and retracted by a pull back cylinder 126. A piston 127 reciprocates within each of the fluid pressure cylinders 125, and have their forward ends abutting against the downwardly extending flanges 128, of the carriages, and pistons 129, reciprocate within each of the pull back cylinders 126, their forward ends projecting through a hole 130 in the extending flanges 128, and is attached to the forward ends of the pistons 127, and a collar 131 near the forward end of the pistons 129 abuts against the flanges 128 of the carriages on the opposite side to that of the pistons 127. In 15 this manner the forward ends of the pistons are secured directly to the flanges of the carriages. The fluid pressure cylinders 125 and pull back cylinders 126 have outwardly extending web members 132, with downwardly flanged outer edges 133, adjustably attached to the frame members 4 and 8, by bolts 134, which pass through slots 135, in the flanged edges thereby allowing for adjustment.

35 In Figure 8 I have illustrated a reciprocating carriage 136, without having lateral means of adjustment. The dove-tailed projection 137, is formed integral with the bed of the carriage and the downwardly projecting flange 138, to which the pistons are attached is formed centrally on the carriage, otherwise the construction is the same.

40 Referring now to the fluid pressure controlling means for reciprocating the carriages, and as a set of similar connections are used for each carriage a description of one set will apply to both. The main fluid supply pipe is indicated as 139, having a valve 140, for cutting off the fluid supply 45 to the machine at will. Branch pipes 141 and 142, extend from the main supply 139. The pipe 141 extends to the end of the pull back cylinder 126 and has a controlling valve 143 mounted thereon, and pipe 142 50 extends to the fluid pressure cylinder 125 and has a controlling valve 144, and adjusting valve 145 mounted thereon.

55 When the adjusting valve 145 is opened slightly, the forward feed of the carriage will be very slow and as the valve is opened the forward feed of the carriage will increase.

60 The controlling valves 143 and 144 are three-way valves, as illustrated in Figure 81, and may have as shown in this figure a

needle valve 146, in the exhausts 147 and 148, instead of using the adjusting valve 145, but in this manner of construction the flow of fluid pressure will be controlled from the cylinders.

65 Links 149 and 150 are attached to the stems of valves 143 and 144, each having a slot 151 in their outer ends. Links 152 are keyed to the operating shaft 153, the outer ends being slotted as at 154. The slotted ends of the links 149, 150 and 152 are connected together by means of a bolt 155, which also passes through a link 156, to which is attached a helical spring 157, the opposite end of the helical spring being attached to the frame of the machine, as at 158. The operating shaft 153 has its bearings in extensions 159 of the top side frames 4 and extend therethrough on either side of the machine. On one end of the operating shaft is attached an operating lever 160, having a socket 161 in its upper end for the reception of a spring 162, for projecting the shank 163 of a handle 164, to which is attached a roller 165, for engaging a notch 166 in a catch 167, which is made adjustable by the bolts 168, passing through slots 169. The shank 163 of the handle 164 extends into the socket 161 and is normally projected by means of the spring 162 and is limited in its movements by means of a pin 170, working in a slot 171 in the side of the operating lever 160.

70 Attached to the reciprocating carriage at the side of the machine, is a plate 172, having an inclined lower surface 173, for engaging the upper end 174, of the shank 163, for throwing the operating lever 160 out of engagement with the notch 166. This plate 75 172 is made adjustable by means of the bolts 175 which pass through slots 176 in the plate, by means of which the plate may be adjusted to give a longer or shorter working stroke to the carriage.

75 To the opposite end of the operating shaft, to that on which the operating lever is attached is secured a hand lever 177, for the purpose of throwing the operating lever into engagement with the notch 166, from either side of the machine.

80 In operating my machine I prefer to exhaust the fluid pressure from the cylinder through a connection 178 into the movable clamping head, which has a tubular opening therein as at 179 and jet openings 180, so that the drills may be quenched or cooled at the end of the working stroke.

85 Referring now to the modification and details illustrated in Figures 20, 23, 25 and 26, in which I have shown an upright machine instead of a horizontal one and in which the carriage and parts mounted thereon are of similar construction to the ones described heretofore, as are also the spindle couplings, the movable clamping heads and 90

the fluid pressure means and controlling mechanism and these will be given the same reference numerals as for the horizontal machine.

5 In this modification 181 indicates the base frame of the machine having a vertical slide way 182 upon which is mounted the work receiving table 183 having centrally formed transversely on its upper face a dove-tailed groove 184 to receive the dove-tailed base 185 of a gage or stop 186. A T-notch is formed in the end of the stop or gage 186, for the reception of the T-end of a feed screw 187, extending through a threaded opening in the bracket 188 and operated by means of a hand wheel 189, on its outer end.

Extending upwardly from the base frame 181, are two side frames 190 and a central frame 191, having slide ways 192, on each of the same. Near the upper ends of the side frames 190 and the central frame 191 are mounted a pair of pinion housings 193, each comprising a casting having a front wall 194 with a flange base 195 attached to the frames 190 and 191 and side walls 196 formed integrally therewith and a rear wall 197, made of a flat plate which is attached to the front wall casting by means of bolts 198.

50 Mounted centrally in the pinion housings is a main drive shaft 199, which has keyed thereto the main driving gear, which meshes with the pinions mounted on the drill-spindle driving shafts which are journaled in the bearing members. This construction being the same as above described and illustrated more fully for Figures 3 and 4 the same reference numerals will be given them and a detailed description is not thought necessary. In this construction I have shown clamping wedges 200, at the sides of the drill-spindle journal bearings which are adjustable by means of a set bolt 201 which can be adjusted to take up any wear that may occur, so the bearing will always be held in a rigid position.

55 Mounted on a bracket above each pinion housing is a motor 202, the shaft of each of which is connected directly to the main drive shaft 199.

In this construction it will be noted that the main driving shaft and the drill-spindle driving shafts are all in the same alignment, so the coupling shafts can be rotated in a substantially vertical position thereby reducing the friction and wear on the universal joints.

60 In Figs. 19 and 21 I have illustrated a motor drive construction which I may use with this machine in which a motor 203, having a bevel gear 204, keyed to the outer end of the motor shaft and meshes with a bevel gear 205, attached to the upper end of the main drive shaft 199.

When the drill-spindle is attached to the main drive shaft as illustrated in Figure 20 it is obvious that the drill-spindle of the main drive shaft will rotate in the opposite direction to the drill-spindles on either side thereof and in this case right and left drills will have to be used.

65 In Figure 30, I have illustrated a modification, with this construction all of the drill-spindles will rotate in the same direction, in which 206 indicates the main drive shaft upon which is keyed the main driving gear 207, meshing with idler pinions 208, having their shafts 209 extending into slots 210 in the adjustable bearings 211 and 212 meshing with pinions 212 on the drill-spindle driving shafts 213.

In Figure 29 I have shown a work receiving table similar to that shown in Figure 26 but having the gage or stop 186, reciprocated by means of a lever 214, pivoted to the gage 186 at 215 and to an extending bracket 216 on the work receiving table as at 217, and in Figure 22 I have illustrated another slightly modified form of clamping member and gage which I may use with an upright machine in which the rail 218 is fed to the machine on its side and rests on a contact face plate 219 which has a dove-tailed projection 220, extending into a dove-tailed recess 221 in the integral projection 222 extending from the side of the clamping block. The contact face plate 219 is held in position by means of the wedge bolts 223 and a gage 224 is mounted centrally on the work receiving table which can be raised and lowered as desired, otherwise the construction is similar to that shown and described in Figures 14, 15, 16 and 18 of the drawings.

70 The operation of my machine is as follows:—assuming that the parts of the apparatus are in the position shown in Figures 1 and 2 of the drawings, the upper ends of the operating lever 160 for controlling the supply of fluid pressure, to and from the cylinders for reciprocating the carriages engaging the notches 166, the valves being in the position illustrated in Figure 31, with valves 143, extending to the pull-back cylinders in the exhaust position and with the valves 144 open, for allowing fluid pressure to pass through pipes 142 to the fluid pressure cylinders 125 thereby advancing the carriages with the rapidly rotating drills mounted thereon together with the movable clamping blocks 110, until the contact face plates 119, engage the side of the rails to be drilled, and as the carriages continue to advance they compress the springs 111, thereby holding the rail or rails securely between the movable clamping blocks 110 and the contact face plates 102, of the stationary clamping block 83. As the carriages continue to advance the drills pass through the

web of the rail, at this point of the advanced movement of the carriages the inclined surface 173 of each of the plates 172 engage the upper ends 174 of the operating levers 160, thereby throwing the operating levers out of engagement with the notches 166. When the upper ends of the operating levers 160 are disengaged from the notches 166 the springs 157 attached to the ends of the links 149 and 150 which extend from the stems of the valves 143 and 144 rotates the valves and the operating levers ninety degrees whereby valves 144 will be in their closed position, with the exhaust ports open so that the fluid in the cylinders 125 will be exhausted into the movable clamping head, while valves 143 will be open to allow fluid pressure to flow through pipe connections 141, to the pull-back cylinders 126, for reTRACTING the carriages. The rail or rails having been drilled are now removed from the machine and another rail or rails inserted. The operating levers 160 are then rotated to the position shown in the drawings, which is at the beginning of the working stroke, and the above operation will be repeated.

In Figures 1 and 2 it will be noted that both of the operating levers 160 are in a vertical position or at the beginning of the working stroke, so that both of the carriages will advance simultaneously, the operating levers 160 when released swinging in the opposite direction to each other, but it will be readily understood that I may advance and retract first one carriage and then the other as desired.

In the modification of my machine shown in Figure 20 the operation of the apparatus is substantially the same with the exception that the rails are fed to the machine with their webs horizontally disposed and the carriages reciprocate vertically instead of horizontally and the gage or stop being mounted centrally on the work receiving table and is not adjustable longitudinally of the table, but is reciprocated transversely thereof, however with the construction of the stops or gages shown in Figures 1 and 2, I may use only one of the gages and adjust it centrally if desired.

The contact face plates can be easily adjusted to different positions on the clamping members, and although I have shown only one set of holes for the drills to pass through, a plurality of sets of holes may be formed therein as desired, and when different sizes of rails are to be drilled it is only necessary to change the contact face plates to conform to the contour of the size of the rail to be drilled, and although I have shown for illustration a rail section any other flanged shape or bar may be drilled by changing the contact face plates to the re-

quired size and contour to meet the requirements of the case. 65

It will be noted by referring to the drawings that when one of the pinions 59 on the drill-spindle driving shafts are thrown out of mesh with the main driving gear the drill which it rotates may have to be removed provided it interferes with the work being drilled, and I wish it understood that although I prefer to use water pressure for reciprocating the carriages, I may substitute in place thereof air, steam or any other kind of fluid pressure therefor. 70 75

Although I have shown and described my invention in considerable detail, I do not wish to be limited to the exact and specific details shown and described, but may use such substitutions, modifications or equivalents thereof as are embraced within the scope of my invention or as pointed out in the claims. 80 85

Having thus described my invention, what I claim and desire to secure by Letters Patent is:—

1. In a drilling machine, comprising a frame, a reciprocating carriage, a drill-spindle journaled on the carriage, a pinion housing mounted on the frame, a main drive shaft forming a direct drill-spindle driving shaft having a gear mounted thereon journaled in the pinion housing, a drill-spindle driving shaft having a pinion thereon meshing with the gear mounted on the main driving shaft, a connection between the drill-spindle driving shaft and the drill-spindle, and a band screw bolt for throwing the pinion on the drill-spindle driving shaft into and out of mesh with the gear on the main driving shaft. 90 95 100

2. In a drilling machine, comprising a frame, slide-ways formed thereon, a pair of carriages arranged side by side mounted on the slide-ways, drill-spindles journaled in adjustable bearings mounted on the carriages, a main drive shaft for rotating the drill-spindles, means for throwing the drill-spindles into and out of engagement with the main drive shaft, and fluid pressure means for advancing and retracting the carriages. 105 110 115

3. In a drilling machine, comprising a frame, slide-ways formed thereon, a pair of carriages arranged side by side mounted on the slide-ways, an adjustable face plate upon each carriage, drill-spindles journaled in adjustable bearings mounted on the adjustable face plates of the carriages, adjustable supports mounted upon the face plates, a clamping member resiliently supported by the adjustable supports, a pinion housing mounted upon the frame, a central driving gear mounted upon a drive shaft journaled in the pinion housing, a plurality of drill-spindle driving pinions journaled in movable bear- 120 125

ings arranged around the periphery of the central driving gear and meshing therewith, connections between the drill-spindle driving shafts and the drill-spindles, means for throwing the drill-spindle driving pinions into or out of engagement with the central driving gear, means for advancing the carriages, and means for automatically retracting the carriages.

10 4. In a drilling machine, comprising a frame, slide-ways formed thereon, a pair of carriages arranged side by side mounted on the slide-ways, an adjustable face plate on each carriage, drill-spindles journaled in adjustable bearings mounted on the adjustable face plate of the carriages, a main drive shaft for rotating the drill-spindles, means for throwing the drill-spindles into and out of engagement with the main drive shaft, 20 and fluid pressure means for advancing and retracting the carriages.

5. In a drilling machine, comprising a frame, slide-ways formed thereon, a pair of carriages arranged side by side mounted on the slide-ways, drill-spindles journaled in adjustable bearings mounted on the carriages, adjustable supports mounted upon the carriages, a clamping member supported by the adjustable supports, a main drive 30 shaft for rotating the drill-spindles, means for throwing the drill-spindles into and out of engagement with the main drive shaft, fluid pressure means for advancing the carriages, and fluid pressure means for automatically retracting the carriages at the end of the working stroke.

6. In a drilling machine, comprising a frame, slide-ways formed thereon, a pair of carriages arranged side by side mounted on the slide-ways, an adjustable face plate on each carriage, drill-spindles journaled in adjustable bearings mounted on the adjustable face plates of the carriages, adjustable supports mounted upon the face plates, a clamping member supported by the adjustable supports, a main drive shaft for rotating the drill-spindles, means for throwing the drill-spindles into and out of engagement with the main drive shaft, fluid pressure means for advancing the carriages, and fluid pressure means for automatically retracting the carriages at the end of the working stroke.

7. In a drilling machine, comprising a frame, slide-ways formed thereon, a carriage mounted on the slide-ways, drill-spindles journaled in adjustable bearings mounted on the carriage, a pinion housing mounted upon the frame, a main driving shaft having a gear mounted thereon journaled in the pinion housing, a plurality of drill-spindle driving shafts mounted in movable journal bearings in the pinion housing, each having a pinion mounted thereon meshing with the

gear on the main driving shaft, a connection 65 between each of the drill-spindle driving shafts and the drill-spindles, and means for throwing the pinions on the drill-spindle driving shafts into or out of mesh with the gear on the main driving shaft.

8. In a drilling machine, comprising a frame, slide-ways formed thereon, a carriage mounted on the slide-ways, drill-spindles journaled in adjustable bearings mounted on the carriage, a pinion housing mounted upon the frame, a main driving shaft having a gear mounted thereon journaled in the pinion housing, a plurality of drill-spindle driving shafts mounted in movable journal bearings in the pinion housing, each having a pinion mounted thereon meshing with the gear on the main driving shaft, a universal connection between each of the drill-spindle driving shafts and the drill-spindles, a wheel screw bolt attached to the movable bearings 80 of the drill-spindle driving shafts for throwing the pinions thereon into or out of mesh with the gear on the main driving shaft, and means for advancing and retracting the carriage.

9. In a drilling machine, comprising a pinion housing, a main drive shaft having a gear mounted thereon journaled centrally in the pinion housing, a plurality of drill-spindle driving shafts each having a pinion mounted thereon for meshing with the gear on the main drive shaft and journaled in movable bearings in the pinion housing arranged around the periphery of the gear on the main drive shaft, said movable bearings 100 for the drill-spindle driving shafts having bosses extending therefrom into slots in the pinion housing, a wheel screw bolt having its inner end attached to each of the movable bearings of the drill-spindle driving shafts, and each wheel screw bolt extending through a threaded opening in the pinion housing, and a hand wheel on the outer end of each wheel screw bolt for throwing the pinions on the drill-spindle driving shafts into or 110 out of mesh with the gear on the main drive shaft.

10. In a drilling machine, comprising a pinion housing, a main drive shaft having a gear mounted thereon journaled centrally in stationary bearings in the pinion housing, a plurality of drill-spindle driving shafts, each having a pinion mounted thereon for meshing with the gear on the main drive shaft and journaled in movable bearings in the pinion housing arranged around the periphery of the gear on the main drive shaft, slide-ways formed in the pinion housing for the reception of the movable bearings for each of the drill-spindle driving shafts, 120 bosses extending outwardly therefrom into slots in the pinion housing, and a wheel screw bolt attached to each of the movable 125

- bearings for the drill-spindle driving shafts for throwing the pinions on the drill-spindle driving shafts into or out of mesh with the gear on the main drive shaft.
- 5 11. In a drilling machine, comprising a pinion housing, a main drive shaft having a gear mounted thereon journaled centrally in stationary bearings in the pinion housing, a plurality of movable journal bearings 70 mounted in slide-ways in the pinion housing arranged around the periphery of the gear on the main drive shaft, said movable journal bearings each being bifurcated centrally, bosses extending outwardly from the movable journal bearings into slots in the pinion housing on either side of the bifurcated central portion of the movable bearings, a drill-spindle driving shaft mounted in journal bearings formed in the bosses of each of the movable journal bearings, a pinion mounted on each of the drill-spindle driving shafts in the bifurcation of each movable bearing, and a wheel screw bolt attached to each of the movable journal bearings for 80 throwing the pinions on the drill-spindle driving shafts into or out of mesh with the gear on the main drive shaft.
- 20 12. In a drilling machine, comprising a pinion housing, a main drive shaft having a gear mounted thereon journaled centrally in stationary bearings in the pinion housing, a plurality of drill-spindle driving shafts each having a pinion mounted thereon journaled in movable bearings in the pinion housing, and arranged around the periphery of the gear on the main drive shaft, means for throwing the pinion and gear into or out of mesh with each other and adjustable wedges for clamping the movable bearings in their 90 adjusted position.
- 30 13. In a drilling machine, comprising a stationary frame, slideways formed thereon, a carriage mounted on the slide-ways, drill-spindles journaled in bearings mounted on the carriage, means for rotating the drill-spindles, adjustable supports mounted upon the carriage, a clamping member resiliently supported by the adjustable supports, fluid pressure means for reciprocating the carriage, and means controlled by the advancing movement of the carriage for automatically retracting the carriage.
- 35 14. In a drilling machine, comprising a stationary frame, slide-ways formed thereon, a carriage mounted on the slide-ways, drill-spindles journaled in adjustable bearings mounted on the carriage, means for rotating the drill-spindles, adjustable supports mounted upon the carriage, a clamping member resiliently supported by the adjustable supports, means for simultaneously shifting the drill-spindle bearings and adjustable supports laterally of the line of feed, fluid pressure means for reciprocating the carriage, and means controlled by the ad- 100
- vancing movement of the carriage for automatically retracting the carriage.
- 40 15. In a drilling machine, comprising a stationary frame, slide-ways formed thereon, a carriage mounted on the slide-ways, an adjustable face plate on the carriage, a plurality of drill-spindles journaled in adjustable bearings mounted on the face plate on the carriage, means for rotating the drill-spindles, adjustable supports mounted on the face plate, a clamping member resiliently supported by the adjustable supports, means for simultaneously shifting the face plate with the drill-spindle bearings and adjustable supports mounted thereon laterally of the carriage, and means controlled by the advanced movement of the carriage for automatically retracting the carriage.
- 45 16. In a drilling machine, comprising a stationary frame, slide-ways formed thereon, a carriage reciprocated by fluid pressure mounted on the slide-ways, an adjustable face plate on the carriage, a dove-tailed projection on the face plate having a rack thereon, a plurality of drill-spindles journaled in adjustable bearings mounted on the adjustable face plate and retained in position by the dove-tailed projection, means for rotating the drill-spindles, adjustable supports mounted on the face plate, a socket in the upper end of each adjustable support, a bolt passing through the socket of each adjustable support, a clamping member attached to one end of each bolt, a spring surrounding the intermediate portion of each bolt, the ends engaging the side of the clamping member and sockets, means for simultaneously shifting the face plate with the drill-spindle bearings and adjustable supports mounted thereon laterally of the carriage, an operating lever for engaging a notch on the stationary frame for controlling the fluid pressure for advancing the carriage, and means on the carriage for releasing the operating lever from the notch for automatically retracting the carriage.
- 50 17. In a drilling machine, comprising a stationary frame, slide-ways formed thereon, a carriage mounted on the slide-ways, an adjustable face plate on the carriage, fluid pressure cylinders for reciprocating the carriages, a dove-tailed projection on the face plate having a rack thereon, a plurality of drill-spindles journaled in adjustable bearings having dove-tailed recesses and mounted on the adjustable face plate and retained in position by the dove-tailed projection, a shaft extending through each of the drill-spindle bearings, a pinion mounted on the shaft engaging the rack on the dove-tailed projection, a hand wheel on the outer end of each shaft, means for rotating the drill-spindles, adjustable supports mounted on the face plate and retained in position by the dove-tailed projection and having means 110
- 55 60 65 70 75 80 85 90 95 100 105 110 115 120 125 130

- of adjustment similar to the drill-spindle journal bearings, a socket in the upper end of each adjustable support, a bolt passing through the socket of each adjustable support, a clamping member attached to one end of each bolt, a spring surrounding the intermediate portion of each bolt, the ends of the spring engaging the clamping member and the socket, means for simultaneously shifting the face plate with the drill-spindle bearings and adjustable supports mounted thereon laterally of the carriage, an operating lever for engaging an adjustable notch on the stationary frame for controlling the fluid pressure for advancing the carriage, means on the carriage for releasing the operating lever from the notch for automatically retracting the carriage, and a connection between the fluid pressure cylinders and a clamping member for exhausting the fluid pressure into the clamping member.
18. In a drilling machine, comprising a stationary frame, slide-ways formed thereon, a pair of carriages mounted on the slide-ways, drill-spindles journaled in adjustable bearings mounted on the carriages, means for rotating the drill-spindles, adjustable supports mounted upon each carriage, a clamping member on each carriage resiliently supported by the adjustable supports, fluid pressure means for reciprocating each carriage, and means controlled by the advancing movement of each carriage for automatically retracting both carriages either separately or simultaneously, substantially as described.
19. In a drilling machine, comprising a work receiving table, a stationary clamping block mounted thereon, means for securing the clamping block to the work receiving table, a stop mounted on the work receiving table, a contact face plate attached to one side of the clamping block, a stationary frame, slide-ways formed thereon, a carriage mounted on the slide-ways opposite the stationary clamping block, drill-spindles journaled in bearings mounted on the carriage, means for rotating the drill-spindles, adjustable supports mounted upon the carriage, a clamping member resiliently supported by the adjustable supports, fluid pressure means for reciprocating the carriage, and means controlled by the advancing movement of the carriage for automatically retracting the carriage.
20. In a drilling machine, comprising a frame, slide-ways formed thereon, a carriage mounted on the slide-ways, a plurality of drill-spindles each journaled in a bearing mounted on the carriage, a pinion housing, drill-spindle driving shafts each mounted in a bearing adapted to be reciprocated in slide-ways formed in the pinion housing, a main drive shaft journaled in the pinion housing adapted to form a direct drill-spindle driv-
- ing shaft and for rotating the plurality of drill-spindles, and means for throwing the drill-spindles into or out of engagement with the main drive shaft.
21. In a drilling machine, comprising a frame, slide-ways formed thereon, a carriage reciprocated by fluid pressure mounted on the slide-ways, a plurality of drill-spindles each journaled in an adjustable bearing mounted on the carriage, a pinion housing, a main drive shaft journaled in the pinion housing forming a direct drill-spindle driving shaft having a gear mounted thereon, drill-spindle driving shafts having pinions mounted thereon for meshing with the gear on the main drive shaft journaled in slide-ways formed in the pinion housing, universal coupling connections between the drill-spindle driving shafts and the drill-spindles, and means for throwing the pinions on the drill-spindle driving shaft into or out of engagement with the gear on the main drive shaft.
22. In a drilling machine, comprising a frame, a slide-way formed thereon, a carriage mounted on the slide-way, a drill-spindle journaled in a bearing mounted on the carriage, a pinion housing mounted on the frame, a main drive shaft forming a direct drill-spindle driving shaft journaled in the pinion housing having a gear mounted thereon, a drill-spindle driving shaft having a pinion mounted thereon meshing with the gear on the main driving shaft and journaled in a bearing adapted for radial adjustment in slide-ways formed in the pinion housing, a connection between the drill-spindle and the drill-spindle driving shaft, and a hand screw bolt attached to the bearing for throwing the pinion mounted on the drill-spindle driving shaft into or out of engagement with the main driving gear.
23. In a drilling machine, comprising a frame, a reciprocating carriage, a drill-spindle journaled in a bearing mounted upon the carriage, a pinion housing mounted on the frame, a main drive shaft forming a direct drill-spindle driving shaft having a gear thereon journaled in the pinion housing, a drill-spindle driving shaft mounted in a journal bearing adapted to be reciprocated in a slide-way formed in the pinion housing and having a pinion thereon meshing with the gear on the main driving shaft, a connection between the drill-spindle driving shaft and the drill-spindle, and a hand screw bolt attached to the journal bearing for throwing the pinion on the drill-spindle driving shaft into or out of mesh with the gear on the main driving shaft.
24. In a drilling machine, comprising a frame, slide-ways formed thereon, a reciprocating carriage mounted upon the slide-ways, a plurality of drill-spindles journaled in bearings mounted upon the carriage, a

pinion housing mounted upon the frame, a main drive shaft forming a direct drill-spindle driving shaft having a gear thereon journaled in the pinion housing, a plurality of drill-spindle driving shafts journaled in bearings each adapted to be reciprocated in slide-ways formed in the pinion housing, a pinion mounted on each of the drill-spindle driving shafts meshing with the gear on the main drive shaft, a connection between each of the drill-spindle driving shafts, and the drill-spindles, and hand screw bolts attached to the journal bearings for throwing the pinions on the drill-spindle driving shafts into or out of mesh with the gear on the driving shaft.

25. In a drilling machine, comprising a frame, slide-ways formed thereon, a carriage automatically reciprocated by fluid pressure mounted on the slide-ways, a plurality of drill-spindles journaled in bearings mounted on the carriage, means for adjusting all of the drill-spindle journal bearings simultaneously, a drive shaft forming a direct drill-spindle driving shaft having a gear mounted thereon, drill-spindle driving shafts having pinions mounted thereon for meshing with the gear on the main drive shaft, connections between the drill-spindles and the drill-spindle driving shafts, and a screw feeding means for throwing the pinions into or out of mesh with the gear on the main drive shaft.

26. In a drilling machine, comprising a frame, slide-ways formed thereon, a carriage reciprocated by fluid pressure mounted on the slide-ways, a plurality of drill-spindles each journaled in an adjustable bearing mounted on the carriage means for adjusting the drill-spindle journal bearings separately or in multiple at one operation independent of the carriage, a main drive shaft forming a direct drill-spindle driving shaft journaled in a stationary bearing in a pinion housing having a gear mounted thereon, drill-spindle driving shafts journaled in movable bearings in the pinion housing, pinions mounted thereon for meshing with the gear on the main drive shaft, a universal coupling connection between each of the drill-spindle driving shafts and the drill-spindles and means for throwing the pinions on the drill-spindle driving shafts into or out of mesh with the gear on the main drive shaft.

27. In a drilling machine, comprising a stationary frame, a slide-way formed thereon, a carriage automatically reciprocated by fluid pressure mounted on the slide-way, drill-spindles mounted in bearings upon the carriage, means for adjusting the drill-spindle journal bearings separately or in multiple at one operation independent of the carriage, a pinion housing mounted upon the stationary frame, a central driving

gear mounted upon a driving shaft journaled in the pinion housing, a plurality of drill-spindle driving shafts journaled in bearings adapted to be adjusted in slide-ways formed in the pinion housing arranged radially around the periphery of the central driving gear and meshing therewith, connections between the drill-spindle driving shafts and the drill-spindles, and screw feeding means for throwing the drill-spindle driving pinions into and out of engagement with the central driving gear.

28. In a drilling machine, comprising a frame, slide-ways formed thereon, a plurality of carriages reciprocated by fluid pressure mounted on the slide-ways, a plurality of drill-spindles journaled in bearings mounted on each of the carriages, means for adjusting the drill-spindle journal bearings separately or in multiple at one operation independent of the carriage, a main drive shaft forming a direct drill-spindle driving shaft for rotating the drill-spindles, and means for throwing the drill-spindles into and out of engagement with the main drive shaft.

29. In a drilling machine, comprising a frame, slide-ways formed thereon, a plurality of carriages mounted on the slide-ways, fluid pressure means for advancing and retracting the carriages, a plurality of drill-spindles journaled in bearings mounted on each of the carriages, means for adjusting the drill-spindle journal bearings separately or in multiple at one operation independent of the carriage, a main drive shaft forming a direct drill-spindle driving shaft for rotating the drill-spindles, and screw feeding means for throwing the drill-spindles into and out of engagement with the main drive shaft.

30. In a drilling machine, comprising a frame, slideways formed thereon, a plurality of carriages mounted on the slide-ways, fluid pressure means for advancing and retracting the carriages, means for controlling the supply of fluid pressure for advancing the carriages, means for automatically retracting the carriages, a plurality of drill-spindles journaled in bearings mounted on each of the carriages, means for adjusting the drill-spindle journal bearings separately or in multiple at one operation independent of the carriages, a main drive shaft forming a direct drill-spindle driving shaft for rotating the drill-spindles, and a screw feeding means for throwing the drill-spindles into and out of engagement with the main drive shaft.

31. In a drilling machine, comprising a frame, slide-ways formed thereon, a plurality of carriages mounted on the slide-ways, a plurality of drill-spindles journaled in bearings mounted on each of the carriages, means for adjusting the drill-spindle

- journal bearings separately or in multiple at one operation independent of the carriages, a pinion housing mounted upon the frame, a central driving gear mounted upon a drive shaft journaled in the pinion housing, forming a direct drill-spindle driving shaft, a plurality of drill-spindle driving pinions journaled in bearings arranged in slide-ways formed in the pinion housing around the periphery of the central driving gear and meshing therewith, connections between the drill-spindle driving shafts and the drill-spindles, and fluid pressure means for advancing and retracting the carriages.
32. In a drilling machine, comprising a frame, slide-ways formed thereon, a plurality of carriages mounted on the slide-ways, a plurality of drill-spindles journaled in bearings mounted on each of the carriages, a pinion housing mounted upon the frame, a central driving gear mounted upon a drive shaft journaled in the pinion housing, said drive shaft adapted to form a direct drill-spindle driving shaft, a plurality of drill-spindle driving pinions journaled in movable bearings radially arranged in slideways formed in the pinion housing around the periphery of the central driving gear and meshing therewith, connections between the drill-spindle driving shafts and the drill-spindles, and fluid pressure means for advancing the carriages to the end of the working stroke and automatically retracting the carriages at the end of the working stroke.
33. In a drilling machine, comprising a frame, slide-ways formed thereon, a carriage mounted on the slide-ways, a plurality of drill-spindles journaled in adjustable bearings mounted on the carriage, a centrally mounted drill-spindle drive shaft for rotating all of the drill-spindles simultaneously, means for adjusting all of the drill-spindle journal bearings simultaneously independent of the carriage, and means for throwing into or out of engagement with the means of rotation one or more of the drill-spindles as desired.
34. In a drilling machine, comprising a pinion housing, a main drive shaft forming a direct drill-spindle driving shaft having a gear mounted thereon journaled in the pinion housing, a drill-spindle driving shaft having a gear mounted thereon journaled in a movable bearing in the pinion housing and meshing with the gear on the main drive shaft, and a screw feeding means for throwing the gear on the drill-spindle driving shaft into or out of mesh with the gear on the main drive shaft.
35. In a drilling machine, comprising a pinion housing, a main drive shaft forming a direct drill-spindle driving shaft having a gear mounted thereon journaled in the pinion housing, a drill-spindle driving shaft having a pinion mounted thereon journaled in a bearing adapted to reciprocate in a slide-way in the pinion housing and a screw feeding means for throwing the pinion and gear into or out of mesh with each other.
36. In a drilling machine, comprising a pinion housing, a main drive shaft forming a direct drill-spindle driving shaft having a gear mounted thereon journaled in the pinion housing, a plurality of drill-spindle driving shafts each having a pinion mounted thereon for meshing with the gear on the main drive shaft and journaled in bearings adapted to reciprocate in slide-ways formed in the pinion housing radially around the periphery of the gear on the main drive shaft, and screw feeding means for throwing the pinion and gear into or out of mesh with each other.
37. In a drilling machine, comprising a pinion housing, a main drive shaft having a gear mounted thereon journaled centrally in the pinion housing, a plurality of drill-spindle driving shafts each having a pinion mounted thereon for meshing with the gear on the main drive shaft and journaled in movable bearings in the pinion housing arranged in slide-ways radially around the periphery of the gear on the main drive shaft, and a wheel screw bolt attached to each of the movable bearings of the drill-spindle driving shafts for throwing the pinions on the drill-spindle driving shafts into or out of mesh with the gear on the main drive shaft.
38. In a drilling machine, comprising a pinion housing, a main drive shaft forming a direct drill-spindle driving shaft, a gear mounted on the drive shaft journaled in the pinion housing, a drill-spindle driving shaft having a pinion mounted thereon for engaging the gear journaled in an adjustable bearing in the pinion housing, screw feeding means for throwing the pinion and gear into or out of mesh with each other, and means for clamping the adjustable bearing in its adjusted position.

In witness whereof I hereunto affix my signature.

ELMER S. SEAVER.
